US00D701584S

(12) **United States Design Patent**
Kasbohm

(10) **Patent No.:** **US D701,584 S**
(45) **Date of Patent:** **** Mar. 25, 2014**

(54) **MAGNETIC FIREARM SUPPORTING DEVICE**

(75) Inventor: **Michael J. Kasbohm**, Eden Prairie, MN (US)

(73) Assignee: **SpecTech, Inc.**

(**) Term: **14 Years**

(21) Appl. No.: **29/431,503**

(22) Filed: **Sep. 7, 2012**
